UNITED STATES PATENT OFFICE

NORMAN B. HURD, OF NEWINGTON, CONNECTICUT, ASSIGNOR TO THE AMERICAN HARDWARE CORPORATION, OF NEW BRITAIN, CONNECTICUT, A CORPORATION OF CONNECTICUT

LOCK

Application filed April 23, 1930. Serial No. 446,436.

This invention relates to locks and latches and particularly to locks in which the latch-bolt performs the double function of a latch-bolt and a dead bolt. It consists in providing certain new and improved operating and dead-locking mechanism for the latch-bolt. It is the object of the invention to provide a relatively simple, inexpensive, durable, and efficient operating and dead-locking mechanism for the latch-bolt.

In the accompanying drawings—

Fig. 1 is a side view of a lock embodying my invention with the cap plate of the case removed;

Fig. 2 is a similar view showing the operating parts in a different position and with part of the cap in place;

Fig. 3 is a vertical sectional view of Fig. 1 on substantially a plane through the axis of the door knobs, this view also showing the lock as installed on a door;

Fig. 4 is a perspective view of the latch actuating and dogging lever;

Fig. 5 is a similar view of a hub for controlling said lever;

Fig. 6 is a similar view of the tail end of the latch-bolt.

In the drawings, which show a preferred form of my invention, 5 indicates a lock case. 5^a is a removable cap therefor. 6 indicates part of a door to which the lock is applied. 7 indicates the usual spring latch-bolt having a tail spindle 8 carrying at its rear end a specially formed tail-piece 9, the latter having a forward extension which carries a stop shoulder 22. 10 is the usual latch spring. The lock is provided with the customary inside and outside door knobs, or other manual latch operating means, whereby the latch 7 may be retracted in the well known manner by the usual roll-back mechanism indicated generally at 11. The lock is also provided with any well known form of "stop work" mechanism shown generally at 11^a, whereby the outer door knob 11^b may be dogged as shown in Fig. 1 to prevent retraction of the latch 7 thereby. These "latch retracing" and "stop work" mechanisms are so fully illustrated and so old and well known as to require no detailed description. 12 is a lever

pivoted at 13 on the wall of the case 5. The lower end 14 of this lever stands in front of the tail-piece 9 of the latch so that when said lever is turned clockwise from the position shown in Fig. 1 it will retract said latch, whereas when said lever is turned to, and held in, the position shown in Fig. 2, it will stand behind the shoulder 22 of the latch tail-piece 9 and block or dog the latch-bolt against retraction or retraction. 15 is a cylinder lock, the plug of which carries a roll-back 16. This cylinder lock is so constructed that when operated by the ordinary key, sometimes termed a "pass" key, it will have only a limited turning movement, whereas, when operated by a special key, sometimes termed an "emergency" key, it will have unlimited turning movement. I have shown and fully described such a cylinder lock in my former Patent No. 1,703,845, of February 26, 1929. Suffice it to say in the present case that the roll-back 16 carries a key actuated slide bearing a lug 24 which normally stands as shown in Fig. 1 so that the rotation of said roll-back will be limited by said lug 24

striking against one or the other of two fixed stops 23—25 on the rear of the cylinder. When the outer knob 11^b is dogged as shown in Fig. 1, it requires a key to operate the latch from the outdoor side. Under normal conditions, a "pass" key may be inserted in the cylinder lock so that the roll-back 16 may be turned in a counter-clockwise direction until it encounters the upper end of the lever 12,

whereupon by a slight continued rotation of said key and roll-back in the same direction the lever will be turned in a clockwise direction to retract the latch-bolt 7. This same function may also be performed by the use of a special or "emergency" key. Now, assuming it is desirable to lock the door from the outside so that it cannot be opened by the outer knob or by the use of a "pass" key, in this event, the "emergency" key is employed which displaces the slide so as to move the lug 24 out of the path of the lugs 23—25, thus permitting the roll-back 16 to be turned completely around the axis of its supporting plug. When such a key is used, the roll-back 16 may be turned in a clock-

wise direction, as viewed in Figs. 1 and 2, to cause the hub 17 and the lever 12 to be shifted to the position shown in Fig. 2, wherein its lower end will stand directly behind the stop 5 shoulder 22 on the latch-bolt tail so that, so long as the lever 12 is held in this position, the latch 7 cannot be repressed or retracted by anything. This movement to, and holding of, the lever 12 in the dead-locking position is 10 accomplished through the medium of a hub 17 which is pivotally mounted on the latch case for oscillation. The upper end of this hub has two spaced horns 21—26. When the roll-back 16 is turned in a clockwise direction as viewed in Fig. 1, it will encounter the horn 21 and shift the hub 17 to the position shown in Fig. 2. On this movement the hub engages and rocks the lever 12 to the position shown in Fig. 2, wherein the end of 15 the horn 21 stands under a shoulder formed by the laterally projecting arm 14^a of the lever 12, which horn end positively blocks the lever against movement from its latch dogging position shown in Fig. 2. A spring 20 bearing on one side or the other of a hump 19 on the hub resiliently holds the hub 17 in either of the two positions shown in the drawings. 18 is a thumb turn at the indoor side of the lock for oscillating the hub 17. 25 When the lever 12 stands in the latch dogging position shown in Fig. 2 it is apparent that, even though the roll-back 16 may be given a limited turning movement by the use of a "pass" key, the end of said roll-back 30 cannot reach the lever 12, and consequently the latch cannot be retracted thereby. Furthermore, since the roll-back 16 cannot be turned by the "pass" key beyond the stops 28—25, the hub 17 cannot be operated to release the latch by the "pass" key. To reverse the hub 17 from the outdoor side of the lock, the "emergency" key is employed and turned in a counter-clockwise direction until the roll-back 16 engages the horn 26 of the 35 hub 17, whereupon by a continued rotation of said key the hub 17 is rocked back to the position shown in Fig. 1 and the lever 12 is restored to the position shown in said figure. On this rocking movement, the lower end of 40 the hub 17 presses against the lever 12 in a direction to restore said lever to its latch actuating position shown in Fig. 1. From the foregoing, it appears that whether the "stop work" 11^a is "on" or "off", 45 the holder of an "emergency" key can set the latch actuating and dogging lever 12 in the position shown in Fig. 2 to prevent retraction of the latch-bolt by the outer knob or by a "pass" key. So, also, the user of a room 50 protected by the lock can set the lever 12 by the use of the thumb turn 18 so that retraction of the latch 7 from the outside will be prevented excepting by the use of an "emergency" key. If the stop work 11^a is "on" as 55 shown in Fig. 1, the holder of a "pass" key

for the room guarded by said lock may use the same to enter his room unless the holder of the special or "emergency" key has previously set the lever 12 in the latch dogging position of Fig. 2.

I am aware that various changes and modifications may be made without departure from the scope of this invention as defined in the appended claims.

I claim:

1. In a lock, a lock case, a latch, a latch lever pivoted to said case for actuating the latch, key actuated means for shifting such latch lever for latch retracting purposes, and means operable from the inside of a door for blocking said latch lever against movement to prevent the retraction of said latch thereby.

2. In a lock, a lock casing, a latch, a latch lever pivoted to said case for actuating said latch, and means operable from the inside of a door for shifting said latch lever and blocking the same to prevent retraction of said latch.

3. In a lock, a lock case, a latch, a latch actuator pivoted to said case, key operable means for moving said latch actuator for retracting said latch, and means operable from the inside of the door for shifting said latch actuator out of the path of said key actuated means.

4. In a lock, a lock case, a latch, a latch lever, key actuated means for engaging said latch lever to retract said latch, and means for shifting said latch lever out of the path of said key actuated means and blocking said latch lever against movement in such latter position, whereby said latch will be dead-locked.

5. In a lock, a lock case, a latch, a latch lever pivoted to said case, key operable means for normally moving said latch lever into position for latch retracting purposes, a hub in said latch case, a manual actuator for such hub, said hub being movable by said manual actuator to shift and hold said latch lever in latch dead-locking position.

6. In a lock, a lock case, a latch, a latch lever pivoted on the case for retracting the latch, manual means operable from the indoor side of the lock for dogging said latch, key operable means operable by means of an emergency key for shifting said manually operable means so as to undog said latch.

7. In a lock, a lock case, a latch, a latch actuator pivoted to said case, key operable means normally operable by means of one key to operate said latch actuator for latch retracting purposes, means operable from the inside of the door for dogging said latch and rendering the key operable means inoperative to retract said latch with said key, but operative by a different key to undog said latch and retract the same.

8. In a lock, a lock case, a latch, a latch

actuator, key operable means for normally moving said actuator to retract said latch, means for limiting the rotation of said key operable means by means of one key, means for shifting said latch actuator to a position out of the path of movement of said key operable means, said key operable means being free for unlimited rotation by a different key to shift said latch actuator into the path of said key operable means, whereby said latch may be retracted by means of a key.

9. In a lock, a lock case, a latch, a latch actuator manually operable from the inside of a door, means for dogging said actuator for dead-locking said latch, and key operable means to be actuated from the outside of a door for undogging said latch actuator by means of an emergency key only.

10. In a lock, a lock case, a latch, a pivotally mounted latch lever, a cylinder lock having a roll-back for normal engagement with said latch lever for shifting the same to retract said latch, means for limiting the rotation of said roll-back, and means operable from the inside of a door for shifting said latch lever out of the path of said roll-back.

11. In a lock, a lock case, a latch, a latch lever pivoted on the case for actuating the latch, a cylinder lock having a roll-back for normally shifting said latch lever to retract said latch, a hub in said lock case and manually operable from the inside of a door, said hub being movable to shift and dog said latch lever and dog said latch, said roll-back being operable by an emergency key to shift said hub to undog said latch lever and latch.

12. In a lock, a lock case, a latch, a latch lever pivoted on the case for actuating said latch, said latch lever having a part for engagement with a part of said latch for dogging the same, and means operable from the indoor side of the lock for moving said latch lever to a latch dogging position.

13. In a lock, a lock case, a latch, a latch lever for actuating said latch, a hub manually operable from the inside of the door for moving said latch lever into position to dead-lock said latch, key operable means, said hub having means to be engaged by said key operable means for shifting said hub to cause said latch to be positioned in the dead-locking position and in normal position.

14. In a door lock, a case, a latch, manual latch retracting means at the outdoor side of said lock, stop work mechanism for said means, a combined latch actuating and dogging lever pivoted to said case, a key controlled means operable by either one of two different keys for swinging said lever when the same stands in one position for the purpose of retracting said latch, said key controlled means being operable by only one of said keys to shift said lever to a different position to prevent the retraction of said latch,

with means interposed between said key controlled means and said lever to transmit motion from the former to the latter by the use of said last mentioned key.

15. In a door lock, a case, a latch, manual latch retracting means at the outdoor side of said lock, stop work mechanism for said means, a combined latch actuating and dogging lever pivoted to said case, a key controlled means operable by either one of two different keys for swinging said lever when the same stands in one position for the purpose of retracting said latch, said key controlled means being operable by only one of said keys to shift said lever to a different position to prevent the retraction of said latch, with means interposed between said key controlled means and said lever to transmit motion from the former to the latter by the use of said last mentioned key, and with means for limiting the degree of rotation of said key controlled means when the latter is turned by one of said keys.
